(57) **CLAIM**

The ornamental design for a magnetic therapy device as shown and described.

DESCRIPTION

The patent or application file contains at least one drawing executed in color. Copies of this patent or patent application publication with color drawing(s) will be provided by the Office upon request and payment of the necessary fee.

1. Magnetic therapy device

Fig. 1.1 is a rear view of the magnetic therapy device according to the invention;

Fig. 1.2 is a front view thereof;

Fig. 1.3 is a perspective view thereof;

Fig. 1.4 is a top plan view thereof; and

Fig. 1.5 is a side view thereof.
